UNITED STATES PATENT OFFICE

OTTO A. BOESEL, OF ANSONIA, CONNECTICUT, ASSIGNOR TO THE H. A. MATTHEWS MANUFACTURING COMPANY, OF SEYMOUR, CONNECTICUT, A CORPORATION

HASP FOR LUGGAGE LOCKS

Application filed July 22, 1931. Serial No. 552,378.

This invention relates to an improvement in hasps for luggage locks, particularly suitcases and similar articles, the object being the simple construction in which a hasp is held in the hasp-plate without the use of any means other than the spring and in some cases, without employing a spring; whereby the operation of assembling the parts is simplified and the separation of the hasp from the hasp-plate is avoided.

The invention consists in the construction as hereinafter described and particularly recited in the claims.

In the accompanying drawings:

Fig. 1 is a front view of a hasp for luggage locks constructed in accordance with my invention;

Fig. 2 is a sectional view taken on the line 2—2 of Fig. 1, showing the hasp in its unlocked position;

Fig. 3 is a sectional view taken on the line 3—3 of Fig. 2;

Fig. 4 is a view similar to Fig. 2, with the hasp in the locked position;

Fig. 5 is a similar view showing the hasp as just entering the housing, or in the position just before complete removal;

Fig. 6 is a perspective view of the hasp detached;

Fig. 7 is a perspective view of one form of spring which may be employed;

Fig. 8 is a perspective view of a modified form of spring; and

Fig. 9 is an end view of the same.

In carrying out my invention, I employ a hasp-plate 10 provided on opposite sides with holes 11 by which the hasp-plate may be secured to a piece of luggage. The plate is formed around its edges with a flange 12 and the central portion of the plate is raised to form the housing 13, and in the lower edge of the housing is a transverse slot 14.

The hasp 15 has the usual locking-button 16 and the upper end or nose 17 is offset from the main portion by two bends 18 and 19, forming reverse angles to the hasp-plate.

The slot 14 corresponds in width to the thickness of the hasp-plate so that the nose of the hasp can be passed into the hasp-plate.

After so inserted, a spring 20 is inserted be-

tween the nose 17 and the inner face of the housing 13. This spring is preferably of U shape. After the spring is inserted, it is impossible to remove the hasp for the reason that the additional thickness of the spring 55 prevents the nose 17 from moving forward sufficiently to permit the hasp to be withdrawn. As an additional precaution to prevent their withdrawal, the bend 19 may be formed with a boss 21 which can be crowded 60 through the slot 14, but after the nose has passed into the housing, it is impossible to withdraw it without mutilating the hasp-plate.

Instead of using the U-shaped spring, a 65 T-shaped spring 22 may be employed, the ends of the cross 23 being bowed so as to normally hold the spring inward from the inner face of the housing 13, this spring being inserted in position in the same way as the 70 spring 20 before described, and after the hasp has been inserted into the housing, the thickness of this spring is sufficient to prevent the hasp from being turned to a degree necessary to allow its removal. 75

In some cases, the boss is sufficient to hold the hasp in engagement with the housing without the use of a spring, though for most purposes, a spring is desirable.

With this construction, I provide a hasp 80 for luggage locks consisting of not more than three pieces, namely, the hasp, hasp-plate and spring, and the parts are readily assembled.

I claim:

1. A hasp for luggage locks comprising 85 a hasp formed near its upper end with two reverse bends, a hasp-plate formed with a housing, a slot through which the hasp may pass, and a spring inserted between the nose of the hasp and the inner wall of the housing. 90

2. A hasp for luggage locks comprising a hasp-plate formed with a central housing and with a transverse slot in its lower corner, a hasp formed near its upper end with reverse bends forming an offset nose, and a boss 95 formed on its inner face at the lower end of the nose.

3. A hasp for luggage locks comprising a hasp-plate formed with a central housing and with a transverse slot in its lower corner, a 100

hasp formed near its upper end with reverse bends forming an offset nose, a boss formed on its inner face at the lower end of the nose, and a spring inserted between the nose and 5 inner wall of the housing.

In testimony whereof, I have signed this specification.

OTTO A. BOESEL.
